UNITED STATES PATENT OFFICE.

ERNEST W. HUTTIG, OF PITTSBURGH, PENNSYLVANIA, ASSIGNOR TO GILL BROTHERS COMPANY, OF STEUBENVILLE, OHIO, A CORPORATION OF WEST VIRGINIA.

DESIGN FOR A REFLECTOR-SHADE.

49,649.

Specification for Design.

Patented Sept. 12, 1916.

Application filed July 7, 1916. Serial No. 108,075. Term of patent 7 years.

To all whom it may concern:

Be it known that I, ERNEST W. HUTTIG, a citizen of the United States of America, and resident of Pittsburgh, county of Allegheny, State of Pennsylvania, have invented a certain new, original, and ornamental Design for a Reflector-Shade, of which the following is a specification.

Referring to the drawing, the figure is a perspective view of the shade.

The device consists of a substantially cylindrical urn 1 having top and bottom circular cornices 2 and 3, the cylindrical sur-

face being ornamented with raised portions parallel to the axis and having the appearance of Gothic pillars 4 supporting the top cornice.

I claim:

The ornamental design for a reflector shade, substantially as shown and described.

Signed by me at Pittsburgh, county of Allegheny, this 23 day of June, 1916.

ERNEST W. HUTTIG.
